A. C. DEER

DISCHARGING DEVICE FOR ROTARY CYLINDERS

Filed Nov. 20, 1925

UNITED STATES PATENT OFFICE.

ATLEE CLYDE DEER, OF CHATTANOOGA, TENNESSEE.

DISCHARGING DEVICE FOR ROTARY CYLINDERS.

Application filed November 20, 1925. Serial No. 70,281.

This invention relates to improvements in discharge devices for rotary driers, kilns, and the like, where it is essential or desirable that the interior of the drier or kiln shall be shut off from the atmosphere at all times.

This apparatus is intended for driers, kilns, furnaces, etc., of the rotary type, such as those employed in expelling moisture from limestone, clay or other materials or 10 treating the same thermally as in burning cement clinker, etc., which will hereinafter be termed "driers". It is well known that in the use of such driers with boiler gases or 15 chemically active gases, that for reasons of draft, the comfort and safety of the personnel, and for avoiding losses of heat, the interior of the drier must be shut off from the atmosphere.

Heretofore such devices have been provided with discharge devices which delivered 20 into a receptacle which could be maintained covered, and which was emptied from time to time at irregular intervals by the attendant; or the contents have been discharged directly to the atmosphere in as brief a space 25 of time as possible. In the first case, leaks present about the joint between the cylinder and the receptacle permitted the passage of gases; and in the second case, no attempt 30 was usually made to prevent such flow of gases while discharging.

According to the present invention the end of the rotary cylinder of the drier, kiln, or the like, hereinafter referred to as a drier, 35 is provided with a series of peripherally arranged doors which are held normally closed, and are opened in succession as the corresponding part of the cylinder is at the bottom. These doors permit the discharge 40 of the material from the interior of the cylinder to an annular chamber surrounding the same, from which a second series of similar doors permit the discharge to the atmosphere. By virtue of this invention, the doors 45 are so disposed and actuated that a door of either series is only opened when all doors of the other series are closed; and in this way no direct communication between the interior of the cylinder and the atmosphere is 50 ever afforded.

In the accompanying drawings:

Figure 1 is a side elevation of the rotary cylinder of such a drier, with a portion broken away on line 1—1 of Fig. 2.

Fig. 2 is an end view of the discharge de-

vice with portions of the drier cylinder indicated.

The rotary cylinder 10 of the drier has a feeding worm or like device 11 at one end and the discharge mechanism at the opposite end. It will be understood that it is customary to mount such a cylinder in an inclined direction upon rollers not shown, and to rotate it by a suitable means at a substantially uniform rate of speed, in a counter-clockwise direction, as shown by the arrow in Fig. 2.

The rotary cylinder is closed at the discharge end by a plate 12 having the gas connection 13 through which gas may be admitted or withdrawn, as will be understood by those versed in the art. On the periphery of the cylinder adjacent this plate are formed the pockets 14 which receive the material after passing through the cylinder. Each 75 of these pockets 14 has a door 15 associated therewith, pivotally mounted upon the cylinder structure and solidly fastened to a shaft 16. Each of these shafts passes outward and is supported at the end in a frame 17 attached to the rotary cylinder. A crank arm 18 is solidly connected to each of these shafts and bears at its free end a roller 19 and carries one end of the individual door closing spring 20, the other end of the latter 80 being connected to a suitable stud 20^a of the casing. Each door serves to close the aperture in the respective pocket.

Joined to and forming a sealed joint with the rotary cylinder is a conical casing 21 which has a stiffening partition 21^a which terminates beyond the end of the cylinder in a cylindrical outer casing 22 which has a series of peripheral pockets 23 similar to those at 14, and each having a respective closing door 24 which is solid with a shaft 25 likewise journaled on the casing 22 and in the frame 17. Each of these doors has a shaft 26 at its free end with a roller 27, thereon, and connected to the door closing spring 28, which in turn is connected to the stud 28^a and the casing 22. The pockets 23 receive the material as discharged through the doors 15; and the material is discharged therefrom through the respective door 24 as the latter reaches the bottom position.

The movement of the series of doors 15 and 24 is accomplished by means of the respective cams 29 and 30 which are attached to the standard 32 which supports the rotary 110

cylinder. It will be noted in Fig. 2 that the relative positions of the two series of doors 15 and 24, and their respective cams, is such that, when four doors are utilized in each 5 series, spaced ninety degrees apart in each series, the point of opening of a door in one series is forty-five degrees after the opening of the next preceding door in the other series; and that each door closes less than forty- 10 five degrees after its opening. In this way, no two doors are open at the same time in the illustration shown.

The operation of the device is obvious. As the cylinder revolves, the roller 19 on one 15 of the shafts 16 encounters the cam 29, and the shaft is thereby rocked to open the door 15, so that the material in the pocket 14 is discharged into the annular chamber 22. After a further rotation of say forty degrees, 20 the roller 19 leaves the cam 29, and the door closing spring 20 returns the door 15 to the closed position. Shortly thereafter the roller 27 encounters the cam 30, and the shaft 25 is rocked to open the door 24 and 25 permit the material in the pocket 23 to be discharged to the atmosphere. About forty degrees of rotation thereafter, the roller 27 leaves the cam 30, and the door 24 is closed by its return spring 28. This action repeats itself for each door in each series as it reaches the bottom.

The device is especially adapted for high-temperature driers or roasters, and for those in which offensive gases are to be kept out 35 of the working room where the cylinder is located.

It is obvious that the device may be modified within the scope of the appended claims.

Having thus described the invention, what 40 I claim as new and desire to secure by Letters Patent is:

1. In a drier, a rotary cylinder having a plurality of doors at its discharge end, each 45 of said doors serving to establish when open a free communication from the inside to the outside of said cylinder, a casing surrounding the doors at the discharge end of the drier having a plurality of doors therein, each of said doors serving to establish when 50 open a free communication from the inside to the outside of said casing, and means to successively open and close said doors so that a door of one of said pluralities is opened while all the doors of the other 55 plurality are closed.

2. In a drier, a rotary cylinder, a closed receiving chamber at the discharge end of the drier attached thereto for rotation therewith, a first plurality of doors closing the 60 communication between said cylinder and said chamber, a second plurality of doors closing communication between said chamber and the atmosphere, means to open and

close doors of said first plurality at intervals, each of said doors serving to establish when open a free communication from the inside to the outside of said cylinder, and means to open and close doors of the second plurality, each of said doors serving to establish when open a free communication from 65 the inside to the outside of said casing during the closed intervals of said first plurality. 70

3. In a drier, a rotary cylinder, a closed receiving chamber at the discharge end of the cylinder and connected to rotate with 75 the cylinder, a first plurality of doors closing the communication between said cylinder and said chamber and spaced at regular intervals about the axis of said cylinder, a second plurality of doors closing the communication between said chamber and the atmosphere and likewise spaced at regular intervals about the axis of the cylinder and located in staggered relations to the doors 80 of said first plurality, means to open doors of said first plurality, when in dumping position, each of said doors serving to establish when open a free communication from the inside to the outside of said cylinder, means to open doors of second plurality when in 85 dumping position, each of said doors serving to establish when open a free communication from the inside to the outside of said casing, and means to maintain the doors of each plurality closed while a door of the other plurality is open. 90

4. In a drier, a rotary cylinder having a plurality of pockets at the discharge end, each of said pockets having a radial aperture, a closing door for each of said apertures, a spring to hold said door in normal closing relation to its respective aperture, a closed casing attached to the cylinder and surrounding said doors and adapted to receive material discharged through said doors and having a plurality of pockets thereon, each of the latter pockets having a radial aperture, a closing door for each of said latter apertures, a spring to hold each of 100 said latter doors in normal closing relation to its respective aperture, a first cam located on the cylinder standard and disposed to open one of said first closing doors as it reaches the dumping position for the respective pocket and permit closure thereof before the succeeding latter pocket reaches its dumping position, and a second cam located on the cylinder standard and disposed to 105 open one of said second closing doors as it reaches the dumping position and permit the closure thereof before the succeeding first pocket reaches its dumping position. 115

In testimony whereof, I affix my signature.

ATLEE CLYDE DEER.
